UNITED STATES PATENT OFFICE.

TARGE G. MANDT, OF STOUGHTON, WISCONSIN.

DESIGN FOR A BOLSTER-STAKE FOR VEHICLES.

SPECIFICATION forming part of Design No. 30,369, dated March 21, 1899.

Application filed January 12, 1899. Serial No. 701,996. Term of patent 14 years.

To all whom it may concern:

Be it known that I, TARGE G. MANDT, a citizen of the United States, residing at Stoughton, in the county of Dane and State of Wisconsin, have invented a certain new and useful Design for Bolster-Stakes for Vehicles; and I do hereby declare the following to be a full, clear, and exact description of the invention, such as will enable others skilled in the art to which it appertains to make and use the same.

My invention relates to designs in bolster-stakes for vehicles; and its essential features consist in a base-plate having downwardly-extending ears and an upright projecting from the base upward and formed into a channel-bar shape for a short distance and then terminating in a cylinder.

It further consists in a strip or brace extending from the tube portion down to the base-plate and connecting the two.

The novelty of my design will be better understood by reference to the following specification and the drawing accompanying the same and forming a part hereof.

The figure is a perspective of my design. 25
Like letters denote corresponding parts in the drawing.

Referring to the drawing, A represents the base-plate, provided with the ears B, which are bent downwardly from the base on both 30 sides. The upright D, integral with the base, is formed into a channel-bar shape for a short distance from the base upward and then into a cylinder and terminating in a cylinder at the top. A brace G extends from the base A 35 to the tube E and connects the two parts together.

Having now described my invention, what I claim, and desire to secure by Letters Patent, is— 40

The design for a bolster-stake for vehicles, as described and shown.

In testimony whereof I affix my name in the presence of two witnesses.

TARGE G. MANDT.
